Manus Aszerman

UNITED STATES PATENT OFFICE

MARIA PETRONELLA JOHANNA LAMBOOY, OF BRUSSELS, BELGIUM

VANITY CASE OR THE LIKE

Application filed July 21, 1932, Serial No. 623,850, and in Belgium June 30, 1932.

My present invention relates to vanity cases or bags which actually form one of the most important accessories of a lady's dressing case. The invention relates in a general 5 way to any kind of powder cases, intended to be removably or nonremovably housed or arranged in hand-bags or the like, as well as to powder-boxes forming independent articles.

In any known vanity case the powder is 10 contained in the body of the vanity case, which generally is made of the shape of a flat case or box with a cover hinged thereto or to be screwed thereon. If powder is taken with the usual powder-puff, a portion 15 thereof will always be spread away, even in the case of a careful manipulation. Just upon opening the case the powder will be disengaged therefrom with the well-known objections. Of course such disengagement may 20 be avoided to a certain extent, but to this end the height of the case should be highly increased, which is inadmissible.

According to my present invention, in order to avoid this objection, the powder is 25 contained in a tubular bag, the bottom of which is attached to or forms the bottom wall itself of the powder case. Said bag, made of any desired flexible material, such as leather, fabric or the like, is open at the top, provided 30 with a wire or a rigid or elastic metal spring (or any other material sufficiently rigid for holding the bag open at its upper rim), said wire or spring corresponding in shape to the shape of the transverse section of the bag 35 and having attached to it (by stitchings, a hem or the like) the upper rim of the bag. Practically the open bag will have the shape of a tube placed upright on the inner face of the body of the powder case, with which it 40 is made integral, the upper opening of the bag being practically undistortable, and enabling the powder-puff to be easily introduced without permitting powder to be disengaged therefrom laterally. In order to 45 close the case the wire or spring will be slightly turned around itself and pressed downwardly at the same time, whereby the flexible side wall of the tube or bag will be twisted around its central axis substantially midway 50 its height, thus tightly enclosing the powder,

the wire or metal spring being turned down upon the closed body of the bag. In order to open the case, all that is necessary is to untwist and pull the bag slightly upwardly. A powder or vanity case according to my 55 invention is illustrated by way of non limitative example in the accompanying drawing, wherein:

Fig. 1 shows the vanity or powder case 60 closed.

Fig. 2 shows the vanity case open, the inner powder bag being closed.

Fig. 3 shows the vanity case with its powder containing bag completely open for enabling powder to be taken therefrom.

Fig. 4 shows the inner powder containing bag in an intermediate position.

Fig. 5 is a section on line V—V of Fig. 2.

The vanity case comprises a small flat case, for instance of circular shape, the cover 1 70 of which is connected to the body 2 by means of a hinge 3, the fastening means of any desired type being designated by 4—4'. Said case may be made of any desired rigid or flexible material, and if desired, it may be 75 attached into a lady's hand-bag or form an independent unit itself or in combination with other articles (red pencil or the like).

Attached to the bottom wall of the body 2 80 by any suitable means, such as stitchings, gluing or the like, is a tube 5, the side wall of which is made of flexible material. Said tube is closed at the bottom by the bottom wall of the body 2, whilst at the top it is held open by means of a rigid ring 6, made for 85 instance of wire or a metal spring. The powder is contained in said tube and owing to the undistortability of the upper rim thereof, the powder-puff may be easily inserted into the tube for taking powder therefrom, the open vanity case being for instance held by one hand and the powder containing tube being in an upright position on the bottom wall of the body of the vanity case. In order to close the vanity case, the bag or tube 5 will first be closed. All that is necessary to this end is to slightly turn 90 (about one half revolution) the ring 6, whereby the side wall of the bag or tube will be twisted around itself and the vertical axis 95 100

of the tube, at the same time forming a stric-
ture midway of its height, as clearly shown
in Fig. 4. Thus the powder will be enclosed
in the lower part of the bag, below the point
5 7 in Fig. 4, the portion of the bag above said
point being adapted to be folded together
with the ring 6 upon the bottom, as clearly
shown in Fig. 2, whereupon the cover 1 of the
case may be turned down. It will be obvious
10 that the powder-puff may be placed upon the
closed bag 5 prior to the turning down of
the cover 1.

The powder containing bag may be opened
15 by a reverse manipulation, turning the ring 6
in opposite direction, at the same time pulling
it slightly upwardly. Owing to said
rigid ring 6 and the regular form of the bag
5, the latter will be held in an upright and
open position.

20 It will be obvious that the outline of the
transverse section of the bag 5 may be any
regular polygon and the shape of the vanity
case may be varied in any desired way.
More particularly, said vanity case may be
25 reduced to a single bottom wall supporting
the bag 5 and having a flap adapted to be
turned down upon the closed bag to secure
the latter in its position. The vanity case
may also be made of the shape of a small
30 bill-case with or without clasp.

Having now fully described my said in-
vention, what I claim and desire to secure
by Letters Patent, is:

35 In a vanity case intended to contain pow-
der, the combination with a tubular body
made of flexible material and adapted to close
over said powder by twisting said body
around the axis thereof and producing pleats
40 therein, thereby folding said tubular body
over the powder, of a case comprising a bot-
tom portion on which is secured, and which
forms the bottom of, the said tubular body,
a cover portion hinged directly to the said
45 bottom portion and adapted to close her-
metically over said bottom portion only
when said tubular body is in twisted and flat-
tened position over the powder, and fasten-
ing means between said bottom and cover
50 portions.

50 MARIA PETRONELLA JOHANNA LAMBOOY.
